UNITED STATES PATENT OFFICE

91,005

DESIGN FOR A WASHING MACHINE TUB

Alpheus W. Altorfer, Peoria, Ill.

Application June 5, 1933. Serial No. 48,290

Term of patent 14 years

To all whom it may concern:

Be it known that I, ALPHEUS W. ALTORFER, a citizen of the United States, residing a Peoria, in the county of Peoria and State of Illinois, have invented a new, original, and ornamental Design for a Washing Machine Tub, of which the following is a specification, reference being had to the accompanying drawing, forming part hereof.

The figure is a perspective view of a washing machine tub, showing my new design.

I claim:

The ornamental design for a washing machine tub, as shown.

ALPHEUS W. ALTORFER.
